UNITED STATES PATENT OFFICE.

ERNEST R. SWANSON, OF CRANSTON, RHODE ISLAND, ASSIGNOR TO UNIVERSAL WINDING COMPANY, OF BOSTON, MASSACHUSETTS, A CORPORATION OF MASSACHUSETTS.

WINDING MACHINE.

Application filed January 13, 1927. Serial No. 160,966.

This invention relates to improvements in winding machines for winding cops, cones or packages of yarn, thread and other attenuated material, and particularly to winding machines in which the cop or package is rotated through contact with a friction drive-roll or drum.

The present invention is directed more particularly to the means for controlling the movement of the cop- or cone-holder away from the driving-drum as the package builds up thereon and for effecting the automatic stopping of the machine when the cop or package reaches a predetermined diameter.

One object of the invention is to provide a machine of the type specified in which the stopping-mechanism may be set to wind packages of any predetermined diameter through a simple adjustment of the control-

means. Another object of the invention is to provide a stopping-mechanism which automatically removes the cop from contact with the drive-roll after it has reached the predetermined diameter and which also disengages the strand of yarn or thread from the continuously-operated traversing thread-guide.

Another object of the invention is to provide means for resetting the stopping-mechanism of the winding machine under manual control to prevent unwarranted stopping of the machine before the winding operation gets under way to pick up the thread and take up the slack in the delivering strand.

Another object of the invention is to provide a controlling- and stopping-mechanism for the winding machine which is more efficient in operation and less liable to derangement or getting out of order.

Further objects of the improvement are set forth in the following specification which describes a preferred embodiment of the invention as illustrated in the accompanying drawings. In the drawings:

Fig. 1 is a front elevation of one unit of a cone-winding machine showing the essential elements of the winding mechanism;

Fig. 2 is an end elevation of the same;

Fig. 3 is a detailed view of a portion of the stopping-mechanism of the machine showing the parts in the relation they assume when the winding is arrested;

Fig. 4 is a similar view showing the same parts in position at the start of the wind-

ing operation and illustrating the manual control therefor;

Fig. 5 is a detailed view of the ratchet cop-lifting device of the stopping-mechanism;

Fig. 6 is a detailed view of the detent-means which normally maintains the stopping-mechanism inactive; and

Fig. 7 is a detailed view of the means for securing the dogging-quadrant to the cop-holder arm.

Referring first to Figs. 1 and 2 of the drawings, 2 designates the rotating drive-roll or friction-drum from which the cop or package is driven; 3 the rotating cop-holder or mandrel on which the cop is wound, in the present machine illustrated in the form of a cone-holder; 4 the reciprocating thread-guide which traverses the strand of yarn or thread longitudinally of the cop-holder to deposit it in helical coils thereon; and 5 the rotating cam which reciprocates the thread-guide 4.

The drive-roll 2 is mounted on a rotating shaft 7 which is driven continuously from suitable power means not herein shown. Usually, the power-shaft 7 is continuous for receiving a plurality of drive-rolls arranged at intervals along the machine frame which carries a number of winding units or heads.

In the present embodiment the cone-holder 3 is rotatably mounted on a spindle 8 carried by a bearing 9 which is swiveled at the end of an arm 10, see Fig. 2. The arm 10 is hinged on a pivot-stud 11 held in a bracket

12 mounted on the machine frame-member 6, whereby to support the cone-holder 3 in position to bear against the drive-roll 2 and to adapt it to swing upwardly therefrom in an arcuate path as the cone or package is built up on the holder. The cone-holder 3 is adapted to tilt on its swiveled bearing 9 as it moves upwardly away from the drive-roll 2 to regulate the taper on the periphery of the cone being wound, the mechanism for

controlling this action being illustrated in general at 13 as embodying the construction shown and described in an application for United States Letters Patent Serial Number 126,897, filed August 3, 1926.

The thread-guide 4 is mounted at the front of the drive-roll 2 to adapt it to reciprocate longitudinally thereof. As herein illustrated, the thread-guide 4 projects upwardly from a slide 14 which is slidable

on a horizontal bar or rod 15. A second horizontal bar 16 extends in parallel relation above the rod 15 and is engaged by a hooked bearing 17 on the back of the guide 4 to maintain the latter in erect position as it slides on the rod 15. The rod 15 and bar 16 are secured in place at the front of the machine by means of suitable bearing-blocks 18, see Fig. 2, which clamp them against the vertical arms 19 forming a part of the frame-members 6. The slide 14 is provided with a lug 22 through which extends a stud 23 carrying a bowl or roller 24 at its lower end which engages with the helical groove 25 in the cam 5. As herein shown the cam 5 has a second groove 26 of different pitch in its periphery which may be alternatively employed to reciprocate the guide 4 in the manner as known in the art. The cam 5 is carried on a continuously rotating shaft 27 which extends throughout the length of the machine frame to operate the cams for other winding units mounted thereon. It will be apparent that the rotation of the cam 5 causes the guide 4 to reciprocate back and forth at the front of the drive-roll 2, and the upper end of the guide is inclined inwardly toward the point of contact of the cop with the periphery of the drive-roll and provided with a suitable thread-groove 28 through which the strand y leads to direct it onto the cop. The guide 4 is also provided with a hook 29 overlying its face to adapt it to pick up the strand of thread or yarn to lead it into the thread-groove 28. The above described instrumentalities constitute the essential elements of the winding mechanism of the machine and are similar in general construction and arrangement to those heretofore employed in the art.

It has been noted that as the cop or cone Y, see Fig. 1, builds up on the holder 3 the latter swings upwardly on the arm 10, and suitable dogging-means are usually provided for steadyng the motion of the cone-holder and preventing a retrogressive movement thereof. The present invention contemplates the employment of an improved dogging-mechanism for this purpose which provides for greater simplicity of construction and is adapted to cooperate with the stopping-mechanism of the machine to arrest the winding operation when the cop or package reaches a predetermined diameter or size. As herein illustrated the dogging-mechanism comprises an arcuate slide or quadrant 30 which depends from the swinging arm 10. Referring to Figs. 2 and 7, the quadrant 30 is held in an arcuate slot 31 on the side of the arm 10 and is clamped in position by means of a bolt 32 and washer 33 overlying its side. Through this arrangement the quadrant 30 may be adjusted in the slot to regulate the extent to which it projects below the arm 10, this adjustment

providing for setting the quadrant to trip the stopping-mechanism when the arm 10 has been moved upwardly to a predetermined extent in accordance with the diameter of the cop or package to be wound. 70

The dogging-means which cooperates with the quadrant 30 to act frictionally thereon to prevent retrogressive movement of the arm 10 consists of a sliding rod or bar 35 which also forms the tripping-means or trigger for the stopping-mechanism. As shown in Figs. 2 and 3, the slide 35 is mounted to slide through a slotted bearing 36 formed on an extension 37 of the bracket 12. The slide or bar 35 is provided with two longitudinal slots 38 which are engaged by pins 39 and 40 to hold the slide in suspension; the rearward pin 39 being driven through the sides of the slotted bearing 36 and the forward pin 40 projecting from the side of the bearing-block 18 previously referred to as fastened to the arm 19 of the frame-member 6. At the rearward end of the slide 35 is an upstanding inclined arm 42 formed with a beveled face 43 which is adapted to engage the forward convex face of the quadrant 30, see Fig. 2. A spring 45 is held against the rearward side of the bearing 36 with its opposite end bearing against a pin 46 driven through the slide 35 whereby it acts to urge the slide rearwardly to cause its end 43 to bear against the quadrant 30 to frictionally resist the movement of the quadrant across the slide. As a result of this construction and arrangement the slide 100 or dog 35 is caused to bear against the quadrant 30 to resist the upward swinging movement of the arm 10 as the package wound on the holder 3 increases in diameter and to also act frictionally to check retrogressive 105 or downward movement of the arm. The movement of the cone- or cop-holder 3 away from the drive-roll is thus frictionally controlled to provide a smooth, vibrationless motion whereby the cop or cone is prevented 110 from jumping and rebounding with respect to the drive-roll.

As a novel and improved feature of the present invention the dogging-mechanism is designed to vary the frictional resistance to 115 the movement of the cop- or cone-holder as the cop or cone increases in diameter. That is to say, the dogging action is differential in accordance with the growth of the package, the resistance to the movement of the cone-holder being at its maximum at the beginning of the winding and gradually decreasing as the package grows in size and weight. This differential action is in accordance with a well-known principle of winding based on the fact that more pressure can be applied to the package when a relatively small body or mass surrounds the holder than when the yarn mass reaches a considerable diameter so that it is softer and more 125 130

apt to be broken down. Furthermore, it is desirable to compress the first layers of winding to the maximum density to provide a firm foundation for subsequent layers and this result is obtained by applying the maximum pressure to the cop- or cone-holder at the start of the winding and gradually decreasing the pressure as the package increases in diameter. This result is secured in the present invention by a novel and ingenious arrangement of the quadrant 30 which is disposed in eccentric relation to the pivot 11 of the swinging arm 10. By reference to the dot-and-dash line in Fig. 2, which defines an arc struck on the pivotal axis of the arm 10, it will be noted that the quadrant 30 does not conform to this arc, but on the contrary is disposed eccentric thereto. It will also be noted that the upper part of the quadrant 30 is of greatest eccentricity, being furthest removed from the axis of the arm 10, while the lower depending portion of the quadrant gradually approaches the axis. It will thus be apparent that with the cone-holder 3 bearing against the drive-roll 2 at the start of the winding, as shown in Fig. 2, the slide or dog 35 will be forced back to hold the spring 45 under maximum compression; while as the cone-holder arm 10 rises the diminishing eccentricity of the quadrant 30 will cause the slide 35 to gradually slide to the right to reduce the compression of the spring 45. In this way the friction action of the dog 42 on the quadrant 30 is reduced to gradually decrease the resistance to the sliding motion of the quadrant and thereby the resistance to the upward movement of the cop- or cone-holder 3. It will be observed that through this simple arrangement and construction an efficient mechanism is provided for applying resistance to the movement of the cop- or cone-holder away from the drive-roll with a differential pressure in accordance with the increase in size of the package being wound.

It has been stated that the slide 35 acts as the trip for the stopping-mechanism of the machine, the dog 42 being adapted to slide off from the end of the quadrant 30 after the package has reached a predetermined diameter in accordance with the adjustment of the quadrant on the arm 10. The instrumentalities which cooperate with the slide 35 to arrest the winding operation are illustrated in detail in Figs. 3 to 6 and will be next explained. To arrest the rotation of the cop- or cone-holder 3 the arm 10 is lifted to remove the package from contact with the drive-roll 2 as is the usual practice in machines of the present type. The lifting of the cone-holder 3 is accomplished by positively raising the arm 10 by means of a ratchet-mechanism, shown in detail in Fig. 5, which acts on the quadrant 30. It will be noted from this view that the quadrant 30 is formed with ratchet teeth 49 which are on the rearward side of the quadrant as viewed in Figs. 2, 3 and 4 so that they do not show in full in these views. Adapted to engage the teeth 49 on the quadrant 30 is a pawl 50 which is pivoted at 51 to a swinging lever 52, see Fig. 5. The pawl 50 has a tail-piece 53 acted upon by a plunger 54 which is under the pressure of a spring 55 held in a pocket depending from the lever 52. The spring 55 maintains the pawl 50 in engagement with the teeth 49 and preferably the bearing of the pawl on its pivot 51 is made more or less loose to provide play so that the pawl may adjust itself to the teeth when the quadrant 30 is moved a distance less than the length of a tooth.

The lever 52 is fixedly secured to the end of a rod 56 which is rockably mounted in a bearing 57 forming a part of the bracket 37 on the frame-member 6 as shown in Fig. 2. The rod 56 has a second bearing 48 at the front of the frame-member 6. The rod 56 also forms the lock or detent for maintaining the stopping-mechanism normally inactive, its forward end being bent into a crook at 58 and terminating in an inclined arm 59 formed with a pointed detent-blade 60, see Fig. 6. The detent-blade 60 is adapted to engage a notch or shoulder 61 on a latch-plate 62 which is fastened to the top of a post 63 projecting upwardly from a rockable member 65 to be later described. The latch-plate 62 is adapted to be rocked into the position shown by dotted lines in Fig. 6, whereby the detent-blade 60 is released from the shoulder 61 to cause it to slide along the inclined edge 64 of the plate 62 in the manner and for the purpose as hereinafter explained. The release of the detent-blade 60 permits the rod 56 to be rocked under the influence of a spring 67 which is anchored to the frame member 6 as shown in Fig. 2 with its upper end engaging the hooked end 68 of an arm 69 on the lever 52. A stop-screw 70 screwed through the arm 69 and locked in place by a checknut 71 is adapted to strike against the top of the bracket 37, see Figs. 2 and 5, to limit the rocking-motion of the lever 52 under the action of the spring 67. When the detent-rod 56 is released the spring 67 will rock the lever 52 carried thereon to lift the pawl 50 to a certain extent as regulated by the adjustment of the stop-screw 70. The lifting of the pawl 50 in this manner acts through the ratchet on the quadrant 30 to slide the latter upwardly whereby to raise the arm 10 to lift the package, indicated at Y' in Fig. 3, out of contact with the drive-roll 2 to arrest the winding operation.

It has been noted that the thread-guide 4 is reciprocated continuously and therefore as the cop or cone is lifted away from the

drive-roll 2 to arrest the winding operation it is necessary that the strand y be lifted out of the groove in the guide to prevent the yarn or thread from being cut or broken.

5 The rockable member 65, previously referred to as carrying the latch-plate 62, constitutes the thread-lifter for disengaging the strand y from the thread-guide 4. As shown more particularly in Figs. 1 and 3, the thread-lifter 65 is constructed in the form of a relatively flat plate provided with opposite socketed bearings 74, which are supported on trunnion-pins 75 projecting inwardly from the frame-members 6. Studs 76 are screwed through the bearings 74 to engage beneath the pins 75 to hold the thread-lifter in place on its trunnions to pivotally support it therefrom. As shown in Fig. 2, the thread-lifter 65 normally assumes a position with its upper edge at the rear of and below the guiding-groove 28 in the thread-guide 4, being retained in this position by the engagement of the latch-plate 62 with the detent-blade 60 on the rockable rod 56. The thread-lifter 65 is rocked into the position shown in Fig. 3 to release the detent-rod 56 and to act concurrently to lift the strand y out of the groove in the thread-guide 4 in the manner as later explained. This action of the thread-lifter is effected through the cooperation of instrumentalities as next described.

Referring to Fig. 3, a bifurcated lever 77 is pivoted to the pin 40 which supports the forward end of the slide 35 with its opposite legs straddling the sides of the slide. The lever 77 has an elbow-shaped arm 78 which is formed with an inclined slot 79 engaged by a pin 80 projecting from the side of the slide 35. When the slide 35 is slid into the position shown in Fig. 3 under the pressure of the spring 45 the pin 80 slides in the slot 79 to tilt the elbow-shaped arm 78 of the lever 77 upwardly. The end of the arm 78 of the lever 77 is hooked under a crank-arm 81 which, as shown in Fig. 1, forms part of a wire rod 82 pivotally mounted in lugs 83 on the under side of the thread-lifter 65. The crank-arm 81 has a hook 84 at its end to which is connected a wire link 85. The link 85 is hooked beneath the tail-piece 86 of a knock-off lever 87 which, as shown in Fig. 3, is pivoted on a pin 89 and constitutes the active element for rocking the thread-lifter 65 to release the detent for the stopping-mechanism. The lever 87 is constructed of sheet-metal with a bifurcated portion 88, the sides of which straddle a lever 90 carrying the pivot-pin 89. The lever 90 is pivoted on a pin 91 driven into the side of the frame-member 6, see Fig. 1, and its upper end is bent over at 92 to adapt it to engage a tail-piece 93 projecting at an angle from one of the bearings of the thread-lifter 65. The tail-piece 86 on the lever 87 projects into position to

adapt its end to be engaged by a toothed collar or wheel 95 which is secured to the cam shaft 27 to rotate therewith. A pin 96 projecting from the side of the frame-member 6 limits the upward movement of the tail-piece 86 on the lever 87 whereby when the end of the tail-piece is engaged by a tooth on the wheel 95 the lever will be moved bodily to rock the connected lever 90 in the direction indicated by the arrow α in Fig. 3. This rocking action of the lever 90 brings its bent portion 92 against the tail-piece 93 on the thread-lifter 65 to rock the latter to raise the thread out of the thread-guide while releasing the detent for the stopping-mechanism in the manner as hereinafter more fully explained.

The lever 87 may also be rocked to engage its tail-piece 86 with the toothed wheel 95 to arrest the winding operation when the strand breaks by means of a breakage-lever 125, shown in Figs. 1 and 2. The lever 125 extends forwardly from the rod 82, being rockable on the rod independently thereof. A collar 126 is fast on the rod 82 and has a slot 127 in which the lever 125 plays. This arrangement provides that the lever 125 may rock upwardly without turning the rod 82, but when it drops it engages the end of the slot 127 in the collar 126 to turn the rod 82 to lift its arm 81. In this manner when the breakage-lever 125 is released from the tension of the strand y it will drop to raise the arm 81 to cause it to act through the link 85, see Fig. 3, to carry the tail-piece 86 of the lever 87 into position to be engaged by the teeth on the rotating collar or wheel 95. This arrangement is similar to the usual breakage-lever mechanism for arresting the winding operation when the thread or yarn breaks.

Manually-operable means are provided for releasing the cone-holder 3 to return it into driving connection with the drive-roll 2 and to concurrently reset the stopping-mechanism to start the winding operation. This manually-controlled means also operates to return the thread-lifter to normal position and the instrumentalities employed for this purpose are illustrated in Fig. 4. They comprise essentially a bifurcated frame 100 having opposite legs 101, see Fig. 1, pivoted on the trunnion-pins 75 which support the thread-lifter 65. The two legs 101 of the frame 100 depend below the thread-lifter 65 and are connected by a cross-strip or web 102. Bolted to the cross-strip 102 is a curved handle or starting-lever 105 which reaches outwardly from the front of the machine in convenient position to be grasped by the operator. Referring to Fig. 1, the right-hand leg 101 of the frame 100 is extended upwardly in an inclined arm 106, see also Fig. 4, which has a flat plate-like portion 107 normally lying adjacent and in alignment with the main plate portion of the thread-

lifter 65. The plate 107 is curled over at the top in an extension 108, see Fig. 4, which is adapted to engage beneath the crooked portion 58 of the detent-rod 56 to rock the latter to engage its detent-blade 60 with the latch-plate 62. The arm 106 of the frame 100 is also provided with a web-like extension 109 which is engaged by the hooked end 110 of the slide 35, see Fig. 4. It will thus be observed that when the starting-handle 105 is depressed into the position illustrated in Fig. 4 the frame 100 will be rocked to cause its arm 106 to slide the slide 35 to move its dogging-arm 42 into position to engage the quadrant 30. During this operation the finger or extension 108 on the arm 106 rocks the detent-rod 56 to engage its blade 60 with the latch-plate 62 and this rocking motion of the rod 56 also operates to rock the lever 52 to release the pawl 50 from the ratchet-teeth on the quadrant 30, the functioning of these parts to start the winding operation being more fully explained hereinafter.

A spring 111 normally holds the frame 100 in the position illustrated in Fig. 2 with its extension 108 bearing against a lug or rest 112 on the bearing-block 18. The spring 111 is connected at 113 to the frame 100 with its opposite end anchored to a pin 114 held in the side of the block 18.

Referring to Fig. 4, a bell-crank lever 115 is pivoted on the pin 91 which forms the pivotal support for the lever 90 and one of its arms 116 reaches upwardly and is bent over in a finger 117 which engages a hole 118 in a lug 119 at the end of the cross-strip 102 of the frame 100. The lower arm 120 of the lever 115 is adapted to engage the tail-piece 86 of the lever 87 to depress the latter to hold its end free from the teeth on the wheel 95, the lever 115 being rocked to effect this action as shown in Fig. 4 when the starting lever 105 is depressed to start the winding operation. The method of operation of the complete machine is as follows:

Assuming that the winding has been arrested with the cop- or cone-holder 3 held in raised position above the drive-roll 2 through the means of the ratchet pawl 50 acting on the teeth 49 of the quadrant 30, the machine is prepared for operation by placing a paper shell or tube T on the mandrel or holder. The strand y of yarn or thread is drawn up from its source of supply, not herein shown, and led under the breakage-lever 125, thence across the upper edge of the thread-lifter 65 and its end secured to the cone-tube T.

With the winding operation arrested the parts of the stopping mechanism are in position substantially as shown in Fig. 3. To start the winding the operator grasps the starting-lever 105 and presses it downwardly against the tension of its spring 111, see Fig. 2, to the position illustrated in Fig. 4.

The depression of the lever 105 rocks the frame 100 and the latter acts through its connections 109 and 110 on the slide 35 to withdraw the latter against the tension of its spring 45. The slide 35 is thus drawn back into the position shown in Fig. 4 so that the friction-dog 42 is moved back to clear the quadrant 30 as shown at the right in this view. As soon as the slide 35 has been withdrawn in this manner the further movement of the rocking frame 100 causes its extension 108 to engage the crook or crank 58 at the end of the rod 56 to turn the latter to rock the lever 52 carried at its end. The lever 52 is thus rocked against the tension of its spring 67, see Fig. 5, thereby causing the pin 47 to act against the pawl 50 to cause the latter to be swung away from the teeth 49 on the quadrant 30. Immediately the pawl 50 is released the weight of the arm 10 and the parts carried thereby will cause the arm to swing downwardly on its pivot 11 to lower the cone-holder 3 to bring the surface of the cop-tube carried thereon into contact with the periphery of the continuously rotating drive-roll 2. The contact of the cop-tube with the drive-roll will therefore cause the cop-holder or winding-mandrel to be rotated therefrom in the direction indicated by the arrow b in Fig. 4.

As the cone-holder is lowered against the drive-roll 2 the quadrant 30 slides down into position to adapt the dog 42 to be frictionally engaged with its convex surface after the slide 35 has been released to allow it to slide forward under the action of its spring 45. This release of the slide 35 does not take place, however, until the starting-lever 105 has been released by the operator. Previous to this release of the slide 35 the downward movement of the lever 105 and the rocking action of the frame 100 caused thereby acts through the bell-crank lever 115 to cause the arm 120 of the latter to press the tail 86 of the lever 87 downwardly to remove it from possible contact with the toothed wheel 95. This action of the bell-crank lever 115 thus serves to prevent unwarranted arrest of the winding operation while the strand y of thread or yarn is slack and the breakage-lever 125 dropped so that it will not free the lever 87 or, in other words, lower it away from the toothed wheel 95.

It should be stated that when the thread-lifter 65 is tilted or rocked upwardly through the action of the lever 90 in arresting the winding operation it is held in this position as shown in Fig. 3 by means of the blade 60 of the detent-rod 56 which slides along the inclined edge 64 of the detent-plate 62 to the position shown in dotted lines in Fig. 6. In starting the winding operation, therefore, when the starting-handle 105 is depressed to cause the exten-

sion 108 on the frame 100 to rock the crank arm 58 of the rod 56 the blade 60 will be slid away from this engagement as last described to allow the thread-lifter 65 to drop 5 into the position shown in Fig. 4 under the action of gravity. At this point the blade 60 on the detent-rod 56 is carried into engagement with the detent-shoulder 61 on the plate 62, see full lines in Fig. 6, and this 10 action causes the stopping-mechanism to be locked in inoperative position as shown in Fig. 4. The dropping of the thread-lifter 65 permits the strand *y* of thread or yarn to ride across its upper edge in such relation to the thread-guide 4 that it will be 15 picked up by the hook 29 on the guide to seat it in the groove 28 as shown in Fig. 1. This automatic threading of the thread-guide takes place when the guide reciprocates to the right as shown in Fig. 1, the 20 traverse of the guide in the opposite direction causing the strand to ride up over the curved portion of the hook 29 to adapt it to be picked up at the next reverse movement of the guide. As the strand *y* of yarn 25 feeds to the rotating cone-holder or winding-mandrel 3 its slack is taken up and the breakage-lever 125 is suspended thereby to prevent it from influencing the breakage-lever 87 to cause arrest of the winding operation. The operator can now release the 30 starting-lever 105 and the frame 100 will be returned to normal position as shown in Fig. 2 under the action of its spring 111. 35 With the parts of the mechanism set in this relation the winding operation will continue with the thread-guide 4 transversing the strand *y* back and forth longitudinally of the cone-holder 3 to direct it onto the 40 cop-tube T in a series of helical turns extending from one end of the holder to the other and crossing each other at intervals. The cone or package is thus built up with a series of overlying layers of the helical turns 45 of yarn or thread, the winding operation being continuous until the yarn breaks or is exhausted, or the package reaches a predetermined size.

Should the strand *y* break the breakage-lever 125 will drop to raise the tail 86 of the knock-off lever 87 into the position shown in Fig. 3 to operate the stopping-mechanism of the machine in the manner as previously explained. Likewise, when the cone reaches 55 a predetermined diameter the stopping-mechanism is released through the disengagement of the quadrant 30 from the dog 42 in the manner as next explained. As the quadrant 30 is carried up with the arm 10 supporting 60 the cone-holder 3 its end finally rides off from the dog or extension 42 of the rod 35. This permits the rod 35 to slide to the right under the action of its spring 45 as shown in Fig. 3 and the pin 80 at the opposite end of 65 the rod will thereby act through the slot 79

in the lever 77 to rock the elbow-shaped arm 78 of the latter upwardly. The lever 77 is thus caused to act through the crank arm 81 and link 85 to lift the tail 86 of the knock-off lever 87 to bring it into position to be engaged by the teeth on the wheel 95. The rotation of the wheel 95 will therefore cause the knock-off lever 87 to rock the lever 90, thus acting through the tail-piece 93 on the thread-lever 65 to tilt the latter upwardly to withdraw the strand *y* of thread or yarn from the thread-guide 4.

As before explained, the raising of the thread-lifter 65 releases the detent-shoulder 61 on the plate 62 from the blade 60 at the end of the rod 56, allowing said rod to be rocked under the action of the spring 67 connected to the lever 52. The rocking of the lever 52 acts through the pawl 50 to force the quadrant 30 upwardly whereby the arm 10 is raised to lift the cone-holder 3 to remove the cop or cone from contact with the periphery of the drive-roll 2 as shown in Fig. 3. The rotation of the cone-holder 3 is thus arrested and the strand *y* of yarn or thread released from the thread-guide so that the winding operation ceases until the stopping-mechanism is manually operated again in the manner as previously explained. It has been before noted that the blade 60 on the rod 56 slides along the beveled edge of the detent-plate 62 to the position shown by dotted lines in Fig. 6 to act as a holding-means to maintain the thread-lifter in raised position until the winding operation is started again, and in this way the winding-mechanism is maintained inoperative until the machine is prepared to wind again.

It will be observed from the foregoing that the invention provides an efficient means for controlling the winding operation automatically to cause the winding to be arrested either when the strand breaks or when the cop, cone or package reaches a predetermined diameter. The improvement further provides that when the winding operation is being started slackness in the strand of thread or yarn, vibration of the breakage-lever, or any other abnormal condition cannot act to cause premature or unwarranted arrest of the winding operation.

While I have herein shown a preferred embodiment of the improved machine it is to be understood that various modifications may be made in the structure and arrangement of the parts of its mechanism without departing from the spirit or scope of the invention. Therefore, without limiting myself in this respect, I claim:

1. In a winding machine, the combination 125 with a rotating winding-mandrel, of stopping-mechanism for arresting the rotation of the winding-mandrel, detent-means for normally maintaining the stopping-mechanism inoperative, a slide movable during the 130

growth of the package wound on the mandrel, controlling-means acting against said slide and releasable therefrom when the package reaches a predetermined diameter, and means for releasing the detent-means upon the release of the controlling-means from the slide.

2. In a winding machine, the combination with a rotating winding-mandrel and means to traverse strand material longitudinally of the mandrel, of stopping-mechanism for arresting the rotation of the winding-mandrel, a slide slidable during the growth of the package wound on the mandrel, resiliently operated means adapted to act against the slide and to be released therefrom when the slide has been moved a predetermined distance, and means actuated from said resiliently-operated means to cause the operation of the stopping-mechanism.

3. In a winding machine, the combination with a rotating winding-mandrel and means to traverse strand material longitudinally of said mandrel, of a slide adapted to be moved by and with the growth of the package wound on the mandrel, a member adapted to bear against the slide, resilient means for holding said member against the slide and acting to move said member when the latter is released from the end of the slide, and stopping-mechanism operated from the releasable member to arrest the winding operation when the package reaches a predetermined diameter.

4. In a winding machine, the combination of a rotating drive-roll, a cop-holder adapted to support the cop or package in contact with the drive-roll, a slide connected to be moved by and with the cop-holder as the package increases in diameter, a member bearing against the slide and adapted to be released therefrom when the package reaches a predetermined diameter, and stopping-mechanism operated from said member to remove the cop or package from contact with the drive-roll.

5. In a winding machine, the combination of a rotating drive-roll, a cop-holder adapted to recede from the drive-roll as the cop increases in diameter, a slide movable with the movement of the cop-holder, a member adapted to bear against the slide and to be released from the end thereof when the package reaches a predetermined diameter, and stopping-mechanism operated from said member to remove the cop from contact with the drive-roll.

6. In a winding machine, the combination of a rotating drive-roll, a swinging arm, a cop-holder supported from the arm to adapt it to recede from the drive-roll as the cop increases in diameter, a slide connected to said arm to be moved therefrom during the growth in the winding, a member adapted to bear against said slide to be released from

the end thereof when the cop reaches a predetermined diameter, and stopping-mechanism operated by the release of said member to arrest the winding operation.

7. In a winding machine, the combination of a rotating drive-roll, a cop-holder for supporting the cop in contact with the drive-roll, means for supporting the cop-holder to adapt it to recede from the drive-roll during the growth in the winding, a slide adjustably connected to said supporting means, a member adapted to bear against said slide and to be released from the end thereof when the cop reaches a predetermined diameter, and means operated from said member to remove the cop from contact with the drive-roll.

8. In a winding machine, the combination of a rotating drive-roll, a cop-holder for supporting the cop in contact with the drive-roll, means to permit the separation of the cop-holder and drive-roll as the cop increases in diameter, a slide slidable during the separation of the cop-holder and drive-roll, a member bearing against the slide and adapted to be released from the end thereof when the cop reaches a predetermined diameter, and stopping-mechanism operated by the release of said member to remove the cop from contact with the drive-roll.

9. In a winding machine, the combination of a rotating drive-roll, a cop-holder for supporting the cop in contact with the drive-roll, a swinging arm for supporting the cop-holder to adapt it to move away from the drive-roll as the cop increases in diameter, an arcuate slide projecting from said arm and adjustable thereon to vary its extent of projection, means adapted to bear against said slide and to be released from the end thereof when the cop reaches a predetermined diameter, and stopping-mechanism operated from the release of said means to remove the cop from contact with the drive-roll.

10. In a winding machine, the combination of a rotating drive-roll, a swinging arm, a cop-holder carried by said arm to support the cop in contact with the drive-roll, an arcuate slide projecting from said arm, means for attaching the slide to the arm to adapt it for longitudinal adjustment with respect thereto, controlling-means adapted to bear against the slide and to be released from the end thereof when the cop reaches a predetermined diameter, and stopping-mechanism operated by the release of said controlling-means to remove the cop from contact with the drive-roll.

11. In a winding machine, the combination of a rotating drive-roll, a cop-holder for supporting the cop in contact with the drive-roll, a swinging arm for supporting the cop-holder to adapt it to recede from the drive-roll during the growth in the winding, said arm formed with an arcuate slot in its

- side, an arcuate quadrant adjustable in the slot on the arm, means to secure said quadrant in adjusted position on the arm, a member adapted to bear against the side of the quadrant to be released from the end thereof when the cop reaches a predetermined diameter, and stopping-mechanism operated from the release of said member to remove the cop from contact with the drive-roll.
- 10 12. In a winding machine, the combination of a rotating drive-roll, a cop-holder for supporting the cop in contact with the drive-roll, an arm pivoted on an axis parallel with that of the drive-roll and carrying the cop-holder to adapt it to recede from the roll during the growth in the winding, an arcuate quadrant supported on said arm in eccentric relation with respect to the axis thereof, and a dog adapted to bear against the convex face of the quadrant to apply a differential degree of resistance to the movement of the cop-holder away from the drive-roll from start to finish of the winding.
- 25 13. In a winding machine, the combination of a rotating cop-holder, means for traversing strand material on the holder, means for permitting the separation of the cop-holder and traversing-means during the growth in the cop, an arcuate quadrant movable about a fixed axis during the separation of the cop-holder and traversing-means, said quadrant formed with its arcuate face eccentric to the axis about which it moves, and friction-means bearing against said eccentric arcuate face to apply a differential degree of resistance to the separation of the cop-holder and thread-guide.
14. In a winding machine, the combination of a rotating cop-holder, a guide for traversing strand material on the cop-holder, means to allow a separation between the cop-holder and guide during the growth in the winding, a pivoted member adapted to swing about a fixed axis during the separation of the cop-holder and guide, a quadrant carried on said member with its arcuate face disposed in eccentric relation with respect to the pivotal axis thereof, and a friction-dog bearing against the arcuate face of said quadrant to adapt it to apply a progressively diminishing degree of resistance to the separation of the cop-holder and guide.
- 50 15. In a winding machine, the combination of a rotating drive-roll, a cop-holder for supporting the cop in contact with the drive-roll, a hinged arm for carrying the cop-holder to adapt it to swing about a fixed pivot, an arcuate quadrant depending from the arm and arranged in eccentric relation with respect to the pivotal axis thereof with its lowermost end at the least distance from said axis, and a friction-dog bearing against the convex face of said quadrant to apply a differential degree of resistance to the movement of the cop-holder away from the drive-roll.
16. In a winding machine, the combination of a winding mandrel and means to traverse strand material longitudinally of said mandrel, said mandrel and traversing-means arranged to separate during the growth of the winding on the mandrel, an arcuate quadrant arranged eccentric to a fixed axis, a friction-dog bearing against the curved face of said quadrant, and means to effect a relative sliding action between the quadrant and the dog during the growth of the winding with said dog acting to resist the movement of separation between the winding-mandrel and traversing-means with the degree of resistance diminishing in proportion to the increase in diameter of the winding.
17. In a winding machine, the combination of a winding-mandrel and means to traverse strand material longitudinally thereof, an arcuate quadrant movable about a fixed axis during the growth in the winding on the mandrel, a sliding member adapted to bear against the curved face of the quadrant to be released from the end thereof when the winding reaches a predetermined diameter, a spring to slide said member, and stopping-mechanism operated upon the release of said sliding member to arrest the winding operation.
18. In a winding machine, the combination of a rotating drive-roll, a cop-holder for supporting the cop in contact with the drive-roll, means for permitting a separation between the cop-holder and drive-roll during the growth in the winding, an arcuate quadrant operated from said last named means to move about a fixed axis during the growth in the winding, a member adapted to bear against the arcuate face of the quadrant, a spring for urging the member against the quadrant and to slide said member when it is released from the end of the quadrant, stopping-mechanism operated upon the release of said member to arrest the winding operation, and manually-operated means for withdrawing said member to adapt it to be reengaged with the quadrant at the start of the winding operation.
19. In a winding machine, the combination of a rotating drive-roll, a cop-holder for supporting the cop in contact with the drive-roll, means for carrying the cop-holder to adapt it to recede from the drive-roll during the growth in the winding, an arcuate quadrant movable with said last named means about a fixed axis, a member engaging said quadrant and releasable from the end thereof when the winding reaches a predetermined diameter, and means actuated by the release of said member to act on the

quadrant to lift the cop-holder away from the drive-roll to arrest the winding operation.

20. In a winding machine, the combination of a rotating drive-roll, a cop-holder for supporting the cop in contact with the drive-roll, a swinging arm for carrying the cop-holder to adapt it to recede from the drive-roll with the growth in the winding, a slide carried by said arm and provided with ratchet teeth on its side, a controlling-member engaging the slide and adapted to be released from the end thereof when the cop reaches a predetermined diameter, a pawl for engaging successively with the ratchet teeth on the slide, and means actuated from the release of the controlling-member to operate the pawl to cause it to move the slide to remove the cop from contact with the drive-roll.

21. In a winding machine, the combination of a rotating drive-roll, a cop-holder for supporting the cop in contact with the drive-roll, a slide slideable from the movement of the cop-holder away from the drive-roll during the growth in the winding, said slide formed with ratchet teeth on its side, a rockable detent-rod, means to rock said rod, a pawl engaging the teeth on the slide and rockable from the detent-rod to move the slide to lift the cop from contact with the drive-roll, means for locking the detent-rod against rocking movement, and stopping-mechanism for releasing the detent-rod to cause it to act to arrest the winding operation.

22. In a winding machine, the combination of a rotating drive-roll, a cop-holder for supporting the cop in contact with the drive-roll while adapting it to recede therefrom during the growth in the winding, a slide movable during the growth in the winding and formed with ratchet teeth on its side, a pawl for successively engaging the teeth on the slide during the movement of the latter, a lever for moving the pawl to lift the slide, a rod for rocking said lever, detent-means engaging said rod to normally prevent its rocking action, a spring for rocking the rod, and means for releasing the detent-means to allow the rod to be rocked under the action of the spring in the manner and for the purpose substantially as described.

23. In a winding machine, the combination of a rotating drive-roll, a cop-holder for supporting the cop in contact with the drive-roll and arranged to recede from the roll as the cop increases in diameter, stopping-means for moving the cop away from the drive-roll to arrest the winding operation, detent-means for normally maintaining said stopping-means inoperative, a rotating knock-off member, a knock-off lever engageable with said rotating member to release

the detent-means, a breakage-lever normally suspended from the strand being wound and adapted to drop to engage the knock-off lever with the rotating knock-off element, manually-operated means for resetting the stopping-means to return the cop into contact with the drive-roll, and means operated from said manual means to hold the knock-off lever away from the knock-off element until the breakage-lever is raised by the tension on the strand.

24. In a winding machine, the combination of a rotating drive-roll, a cop-holder for supporting the cop in contact with the drive-roll, means for carrying the cop-holder to adapt it to recede from the drive-roll with the growth in the winding, means for lifting the cop-holder away from the drive-roll to arrest the winding operation, stopping-mechanism for operating the lifting-means, manually-operated means for releasing the lifting-means to return the cop into contact with the drive-roll, and means operated from said manual means to prevent unwarranted action of the stopping-mechanism until the winding operation is underway.

25. In a winding machine, the combination of a rotating drive-roll, a cop-holder for supporting the cop in contact with the drive-roll, a thread-guide for traversing the yarn on the cop, means to shift the cop away from the drive-roll to arrest the winding operation, means to release the strand of yarn or thread from the thread-guide concurrently with the arrest of the winding operation, means to return the cop into contact with the drive-roll, means to concurrently release the strand to adapt it to be reengaged by the thread-guide, and means operative upon the return of the cop into engagement with the drive-roll to prevent unwarranted action of the stopping-means until the strand is reengaged with the thread-guide.

26. In a winding machine, the combination of a rotating drive-roll, a cop-holder for supporting the cop in contact with the drive-roll, means for lifting the cop away from the drive-roll to arrest the winding operation, a rockable rod for operating the lifting means, said rod formed with a crank-arm, a spring to rock said rod, detent-means to hold the rod from rocking under the action of the spring, a member engageable with the crank-arm on the rod to rock the latter to engage it with the detent-means, stopping-mechanism to release the detent-means, and means operable during the rocking of the rod into engagement with the detent-means to prevent premature action of the stopping-mechanism.

27. In a winding machine, the combination of a rotating drive-roll, a cop-holder for supporting the cop in contact with the

drive-roll, means for lifting the cop away from the drive-roll to arrest the winding operation, a rockable rod for operating the lifting-means, said rod formed with a crank-arm, a spring for rocking the rod, a detent for holding the rod from rocking, a knock-off lever for releasing the detent, manually operable means for reengaging the detent with the rod, and means operated from the 10 manual means to prevent the operation of the knock-off lever after the reengagement of the detent-means.

28. In a winding machine, the combination of a rotating drive-roll, a cop-holder 15 for supporting the cop in contact with the drive-roll, a traversing thread-guide, means for lifting the cop away from the drive-roll to arrest the winding operation, a thread-lifter for releasing the strand of yarn or 20 thread from the thread-guide upon the arrest of the winding operation, a knock-off lever for operating the thread-lifter, detent-means carried by the thread-lifter and adapted to normally restrain the cop-lifting 25 means from action, a knock-off lever for rocking the thread-lifter and releasing the detent-means, a hand-lever for returning the thread-lifter to normal position and re-

engaging the detent-means, and means operated from said hand-lever to render the 30 knock-off lever inoperative at the start of the winding operation.

29. In a winding machine, the combination of a rotating drive-roll, a cop-holder for supporting the cop in contact with the 35 drive-roll, means for lifting the cop away from the drive-roll to arrest the winding operation, a rockable rod for operating the lifting-means, said rod formed with a crank-arm and a detent, a traversing thread-guide, a thread-lifter for disengaging the strand of thread from the thread-guide, a detent-member carried by said thread-lifter to normally engage the detent on the rod, a knockoff lever for rocking the thread-lifter 40 to disengage the thread from the guide and to release the detent-means, starting-means adapted to act on the crank-arm to rock the rod to reengage the detent-means therewith, and means operable from the starting-lever 45 to release the knock-off lever to return the thread-lifter to normal position.

In testimony whereof I hereunto affix my signature.

ERNEST R. SWANSON.
